UNITED STATES PATENT OFFICE.

CHARLES H. SPENCER, OF BALTIMORE, MARYLAND.

PLAYER-PNEUMATIC.

1,192,009.

Specification of Letters Patent.

Patented July 25, 1916.

Application filed January 27, 1915. Serial No. 4,680.

To all whom it may concern:

Be it known that I, CHARLES H. SPENCER, a citizen of the United States, residing at the city of Baltimore, State of Maryland, have invented certain new and useful Improvements in Player-Pneumatics, of which the following is a specification.

This invention relates to playing pneumatics.

10 One object is to provide a relatively long, narrow, thin playing pneumatic, whereby the space in the piano casing may be minimized with the result that comparatively little space in the piano casing is required 15 for the playing pneumatics.

Another object is to provide a relatively long, narrow thin bellows embodying among other characteristics a straight flat member, a member hingedly connected to the afore- 20 said member and a fold connecting said members, a chamber located between the inner faces of said members, the chamber having a port leading into the bellows, the bellows having an inlet port and an exhaust 25 port, and a valve operable to control said ports.

Another object resides in the provision of a playing pneumatic embodying, among other characteristics, extreme sensitiveness 30 and positive operation of the few parts constituting the pneumatic.

With the above and other objects in view, the present invention consists in the combination and arrangement of parts herein- 35 after more fully described, illustrated in the accompanying drawing, and particularly pointed out in the appended claims, it being understood that changes may be made in the form, proportion, size and minor de- 40 tails without departing from the spirit or sacrificing any of the advantages of the in- vention.

In the drawings:—Figure 1 is a side elevation of one of my improved pneumatics 45 illustrating adjacent parts in transverse section and in elevation. Fig. 2 is a horizontal longitudinal sectional view on the line 2—2 of Fig. 1. Fig. 3 is a longitudinal vertical sectional view on the line 3—3 of Fig. 2. Fig. 50 4 is an enlarged fragmentary vertical sectional view through the upper portion of one of the playing pneumatics. Fig. 5 is a detail perspective view of one form of connecting means between the fixed and mov- 55 able members of my improved playing pneumatic. Fig. 6 is an enlarged detail perspec-

tive view of the valve operating arm of each playing pneumatic.

Referring more particularly to the accompanying drawing, each pneumatic includes 60 an upper fixed member 10 and a movable member 11, which are connected by a fold 12. The movable member is provided with an extension 13 to contact with and actuate a wippen (not shown). 65

An elbow 14 is fitted tightly in an exhaust aperture 15 formed in the upper fixed member 10 of each pneumatic. This elbow is coupled to the corresponding one of a plurality of nipples 16 projecting from the 70 front face of the wind chest 17 by means of a suitable coupling 18, whereby communication is established between each pneumatic and the wind chest.

The underside of each fixed member 10 is 75 provided with a longitudinal cavity 19 located in advance of the exhaust 15 and leading through said fixed member into said cavity is a small aperture 20. A nipple 21 is fixed in the small aperture 20, to which is 80 connected a tube 22 which leads to a tracker bar (not shown). A chambered partition 23 is glued or otherwise secured to the underside of each fixed member 10 and arranged in longitudinal alinement with the 85 aforesaid longitudinal cavity 19, forming a relatively long narrow chamber 24 in the playing pneumatic. This secondary chamber 24 has communication with the wind chest 17 by way of the respective elbow 14 and 90 the coupling connections between the latter and the wind chest, and it also has a port 25 to establish communication between it and the interior 26' of the respective pneumatic. 95

A U-shaped member B including sides 26 and a connecting web 27 embraces the fixed member and the chambered member at the outer end of the fixed chamber, there being a narrow spacing block 28 between the 100 web 27 and the partition 23 to provide an air space 29, and it is to this U-shaped member B that the movable member 11 of the respective pneumatic is hinged, preferably by fabric or other suitable material 30. This U- 105 shaped member B may be secured in place by glue and, if desired, by the fold 12 or a portion of the material of which the fold is composed which may be wrapped around the pneumatic as indicated at 12' in 110 Fig. 3. If desired, a securing element 31 may pierce the fixed member 10, the parti-

tion 23 and the spacing block 28. Furthermore, if desired, the U-shaped member B may have its sides 26 provided with indentations 32, forming lugs adapted to bite into the edges of the fixed member 10 or other parts of the pneumatic, so as to facilitate firmly securing the member B to the respective pneumatic. A connection of other shape and form than this particularly formed member B may be employed for the performance of the same functions as are ascribed to this particular member B. As shown, however, the member B has a port 33 formed in its web portion 27 and disposed in coaxial alinement with the port 25 in the partition 23.

A valve 34 to control the ports 15, 25 and 33 is employed. This valve is shown as of disk shape and preferably consists of two circular elements of buck skin, fabric, or other suitable material, carried one on each side of a flat spring or other yieldable arm 35, secured at one end to the underside of the partition 23 by suitable fastening means 36. This valve 34 normally closes the port 25 of the respective pneumatic by reason of the yieldable nature and form of the arm 35.

A diaphragm 36' is secured around the edges of the aforesaid cavity 19 of the fixed member 10 of each pneumatic. This diaphragm is preferably loose within its edges for movement toward and away from the cavity, under the influence of pressure and suction.

Secured to the diaphragm throughout a portion of its length is a valve operating arm 37 on the underside of which, intermediate its ends and in alinement with the aforesaid small aperture 20, is a disk 38 having a bleed hole 39 leading through the bleed holes 40 and 40' in the diaphragm and the arm 37, respectively. The free end of the arm 37 is provided with a stem 41 arranged coaxially with the ports 25 and 33 for the purpose of unseating the valve 34 with relation to the port 25, the normal position of the valve, and force it into co-operative relation with the lower port 33 at predetermined times, so as to close the port 33 and provide for a communication between the chamber 24 and the interior of each pneumatic.

My improved pneumatic may be supported in a piano casing (not shown) in any suitable manner. One way in which the pneumatic may be supported is to support the outer ends of the pneumatics in a channeled bar C consisting of upper and lower flanges 42 and 43 respectively connected by a web portion 44. The outer ends of the pneumatics are adapted to fit snugly against the web portion 44 between the flanges 42 and 43 of said bar C, and yet be readily removed from co-operative relation therewith.

To support the inner ends of the pneumatics there is provided a strip 45 arranged in parallel relation with the bar C and also with relation to the wind chest 17, and disposed relatively close to the latter and secured in such position in any suitable manner. In fact the strip 45 may be soldered along its under edge to the wind chest, as indicated at 46, and depend entirely upon the wind chest for its support. Angle irons 47 may be supported on the upper edge of this strip 45, with one angle iron in alinement with each playing pneumatic. For instance, one leg of each angle iron may fit between the strip 45 and the wind chest 17, and the other leg of each angle iron extend laterally over the strip 45. The latter leg of the angle iron has a perforation 47' therein adapted to receive a screw threaded shank 48 of a nut 49 adapted to be screwed into and through the upper fixed member 10 of the respective playing pneumatic and into a block 50, as shown in Fig. 1. This particular means of supporting and securing the playing pneumatics permits free and easy adjustment of the same laterally toward and away from one another for proper positioning with relation to the wipers or other parts of the instrument (not shown), and also permits ready and easy removal of any one of the pneumatics independently one of another. By way of further explanation it may be noted that the pneumatics may be shifted laterally, by reason of their outer ends having sliding movement in the channeled bar C and the angle irons 47 being slidable along the strip 45.

It is well known in the present art that when the various apertures of the music sheet are brought into registration with the apertures in the tracker bar, that pressure or suction is created through tubes leading to the pneumatics. One of these tubes is indicated at 22, and it will be understood that each pneumatic has a tube 22 leading from it to the tracker bar (not shown). The pressure or suction created in the operation of the instrument when the music sheet perforations register with the perforations in the tracker bar causes the diaphragm 36 in this instance to expand and move away from the adjacent wall of the cavity 19, forming an air pocket. This expansion of the diaphragm causes the respective pins 41 to engage the respective valves 34 and force the latter away from the respective upper ports 25 into tight seating relation with the respective lower ports 33. The air may then pass from the respective bellows into the respective chamber 24 and thence from said chamber through the respective exhaust port 15 and through the corresponding elbow 14 into the wind chest 17. The closing of the respective pneumatic causes its extension 13 to lift the re-

spective wippen and thereby actuate the piano action (not shown). Immediately upon the apertures in the music sheet passing out of registration with the respective 5 apertures in the tracker bar, the tubes 22 become closed, and the surplus air in the respective pocket passes through the respective bleed holes 39, 40, and 40', into the chamber 24. This allows the spring arm 35 10 to close the port 25 and force the stem 41 and the operating arm 37 to their upper position. The operating arm 37 is exceedingly small and light and is lifted to its place at the top of the secondary chamber before the 15 suction in the secondary chamber becomes effective by the seating of the valve 34 at the port 25. When port 33 is opened by the valve 34 air at atmospheric pressure enters the chamber 26' and causes the latter to inflate.

From the foregoing it will be seen that my improved playing pneumatic is simple, economical, and durable, and by virtue of my peculiar construction, I am enabled to 25 provide a relatively long, narrow, and thin playing pneumatic.

As the claims in this case are confined to the particular construction of playing pneumatic, it is deemed entirely unnecessary to 30 illustrate the tracker bar and the means of operation of the tracker bar, the piano action, the motive power, etc., for the reason that the piano action, motive power, etc., do not form part of the present invention and 35 may be constituted of elements now common in the art.

What is claimed is:

1. In a playing pneumatic for player pianos a fixed and a movable member, a fold 40 connecting the fixed and the movable members and constituting a bellows which is provided with an inlet port and an exhaust port, a partition in the bellows forming a chamber which is provided with a port arranged in coaxial alinement with the aforesaid inlet port of the bellows, a valve held normally in engagement with said partition port, a diaphragm in the chamber, a valve operating arm operable under the influence 45 of said diaphragm to unseat said valve with relation to said partition port and position the valve in coöperative relation with the inlet port of the bellows to close the latter, the diaphragm having a bleed hole.

55 2. In a playing pneumatic, a bellows composed of a fixed member, a movable member, and a fold connecting said members, the fixed member having an exhaust port and a relatively small aperture, a partition in 60 the bellows to form a chamber therein and into which said small aperture leads, the partition having a port therein, a valve seat member connected to the fixed member and provided with a port, and to which valve seat the movable member of the bellows is

connected, a valve held normally in engagement with the port in said partition, and means in the chamber operable under the influence of pressure or suction through said small aperture of the fixed member to shift 70 said valve from coöperative relation with the partition port into sealing relation with the port in the valve seat member, said means having a bleed hole.

3. In a playing pneumatic, a bellows composed of a fixed member, a valve seat member connected thereto and provided with a port, a movable member hingedly connected to said valve seat member, a fold connected to the fixed and movable members of the bellows, said fixed member having an exhaust port and a relatively small aperture, the underside of the fixed member having a relatively long cavity, a channeled partition in the bellows which coöperates with said cavity to form a chamber within the bellows and into which chamber said aperture leads, said partition member having a port therein arranged in coaxial alinement with the port of the valve seat member, a valve held normally in engagement with the port of the partition member, a diaphragm located in said cavity of the fixed member, a yieldable arm secured in said cavity and provided with a stem disposed in alinement with the axes of said valve seat member port and said partition port and which is movable with the diaphragm under the influence of pressure or suction entering the said chamber through said small aperture in the fixed 100 member so as to shift said valve from the port of the partition member into sealing relation with the port of the valve seat member, the diaphragm having a bleed hole.

4. In a playing pneumatic, a bellows composed of a fixed member, a valve seat member secured to the fixed member and provided with a port, a movable member hingedly connected to said valve seat member, a fold connecting the fixed and movable members, the fixed member having a port and a relatively small aperture, a portion adjacent the fixed member forming a chamber in the bellows into which chamber said small aperture leads, a yieldable arm secured at one end to the underside of the chamber, the chamber having a port leading into the bellows, a valve secured to said arm and normally closing the port leading from the chamber, and means located in the chamber 110 for actuation under the influence of pressure or suction through said small aperture to operate said valve against the tension of said yieldable arm to force the valve from the port of the chamber and hold the valve 115 in tight engagement with the port in said valve seat member.

5. In a playing pneumatic, a bellows comprising a fixed member, a member secured to the fixed member and provided with a port,

a movable member hingedly connected to said ported member, a channeled partition disposed longitudinally in the bellows and co-operating with the fixed member of the bellows to form a relatively long, narrow shallow chamber, the fixed member having a relatively large port leading into the bellows and also provided with an exhaust aperture leading from said chamber, said partition member having a port disposed in coaxial alinement with the port of the aforesaid ported member, a valve located normally over the port of the partition member, a diaphragm in said chamber operable for downward movement in the chamber under the influence of pressure or suction, and a relatively long yieldable arm disposed in the chamber, said arm having a stem and being movable under the influence of downward movement of the diaphragm to cause its stem to engage said valve and shift the latter from the port in the partition into sealing relation with the port of said ported member, said diaphragm having a bleed hole.

6. In a player pneumatic, a relatively long, narrow, thin bellows provided with an exhaust port and a small aperture adjacent thereto, said bellows also having an inlet port, a partition in the bellows forming a relatively long, narrow, shallow chamber in the bellows and from which said exhaust port leads and into which said aperture leads, the partition having a port in coaxial alinement with the aforesaid inlet port of the bellows, a valve normally closing the partition port, a relatively long narrow diaphragm in the chamber normally positioned at the top thereof over the said small aperture and adapted to yield downwardly under the influence of pressure or suction through said small aperture, and a relatively long yieldable arm in the chamber provided with a stem disposed over said valve, said arm being actuated by downward movement of the diaphragm to cause said stem to force said valve from the partition port into engagement with the inlet port of the bellows and thereby establish communication between the chamber and the bellows, said diaphragm and said arm having alining bleed holes and said yieldable arm returning the diaphragm to normal position when the diaphragm is relieved of pressure or suction, the air between the diaphragm and the upper wall of the chamber being forced by said yieldable arm through said bleed holes into said chamber.

7. In a striker player pneumatic for player piano mechanisms, a relatively long, narrow, thin bellows including a flat straight top member, a member hingedly connected to the top member, and a fold connecting said members, the bellows having an inlet port and an exhaust port on opposite sides of the bellows, a partition se-

cured to the top member and constructed to form with the top member a relatively long, narrow chamber located within the bellows adjacent the top member thereof and provided with a port to establish communication with the bellows, the aforesaid exhaust port leading from said chamber through said top member of the bellows, and a pneumatically operated valve mechanism for controlling said ports.

8. A pneumatic for player pianos including a fixed member, a movable member, a fold connecting said members and forming a bellows, said bellows having an inlet port, a partition located in the bellows adjacent the fixed member and with the latter forming a chamber in the upper portion of the bellows, said partition having a port adjacent one end thereof to establish communication between the chamber and the bellows, the chamber having an exhaust port leading from the same at one end thereof opposite the end at which the partition port is located, pneumatically operated valve mechanism for controlling the said ports, and a wind chest connected with said chamber of the bellows.

9. In a striker player pneumatic for player piano mechanisms, a relatively long, narrow, thin bellows including a flat straight top member, a member hingedly connected to the top member and a fold connecting said members, the bellows having an inlet port and an exhaust port, a partition in the bellows connected to the inner face of the flat straight top member to form with the latter a relatively long, narrow chamber located within the bellows adjacent the top member thereof and provided with a port to establish communication between the chamber and the bellows, the aforesaid exhaust port leading from said chamber through said top member of the bellows, the inlet port of the bellows and the port establishing communication between the chambers and the bellows being disposed in alinement, a valve normally closing the communicating port between the chamber and bellows, and a pneumatically operating means to force said valve from its seat into closing relation with the inlet port of the bellows to permit the flow of fluid from the bellows into the chamber and thence through the exhaust port.

10. In a striker player pneumatic for player piano mechanisms, a bellows including a flat top member, a hinged bottom member and a fold connecting said members, a partition in the bellows constructed to form with the flat top member a chamber between the inner faces of said members and provided with a port leading into the bellows, a valve normally closing said port, the bellows having an inlet port adjacent the aforesaid port and also having an exhaust

port leading from said chamber, an arm within the chamber carrying a lateral projection disposed in alinement with the first named port, and a diaphragm operable to 5 move the aforesaid arm to force the lateral projection of the arm into engagement with said valve to unseat the valve with relation to the first named port and hold the valve temporarily in engagement with the inlet 10 port of the bellows.

11. In a striker player pneumatic for player piano mechanisms, a relatively long, narrow, thin bellows including a flat member and a member hingedly connected thereto and provided with an inlet port and an exhaust port, a partition within the bellows to form with the flat member a relatively long, narrow chamber confined within the bellows between the inner faces of the flat 15 member and hinged members and provided with a port communicating with the bellows, and a valve mechanism for controlling said ports.

12. In a striker player pneumatic for player piano mechanisms, a relative long, narrow, thin bellows including a flat member and a member hingedly connected thereto and provided with an inlet port and an exhaust port, a partition within the bellows 20 to form with the flat member a relatively

long, narrow chamber within the bellows between the inner faces of said members and provided with a port communicating with the bellows, and a pneumatically operated valve for controlling said ports. 35

13. In a striker player pneumatic for player piano mechanisms, a bellows including a flat member, a member hingedly connected thereto and a fold connecting said members, the bellows having an exhaust 40 port in said flat member, the bellows also having an inlet port, the flat member having a relatively small aperture therein, a valve mechanism within the bellows for controlling said ports, a diaphragm secured to 45 the under side of the flat member between said exhaust port and one end of the flat member and which extends over said relatively small aperture, and means adjacent the under side of the diaphragm and actuated thereby to open said valve mechanism to permit passage of fluid from the interior 50 of the bellows through said exhaust port.

In testimony whereof I affix my signature in presence of two witnesses.

CHARLES H. SPENCER.
